UNITED STATES PATENT OFFICE

2,577,703

ELECTRIC WATCH

Arthur E. Fillinger, Lancaster, Pa., assignor to
Hamilton Watch Company, Lancaster, Pa.

Application October 31, 1947, Serial No. 783,319

1 Claim. (Cl. 58—28)

1
This invention relates to electric watches of the type in which the watch movement is driven by a periodically advanced ratchet through the medium of an oscillating balance wheel which in turn is driven by an electromagnet.

It is the object of the invention to provide a watch movement so sensitive and delicate in its operation that only the smallest motive power is required to operate it for a comparatively long period of time.

To enclose in the ordinary watch-case of today a battery and a movement operated by the battery renders it necessary to have the movement operate almost frictionless and to time the motion of the ratchet arm with the electromagnetic impulse given to the balance wheel and to combine both the mechanical impulse and the electrical contact to reduce the energy required to drive the watch.

It is a further object of the present invention to provide a spring pressed center wheel which is frictionally held against a shoulder of the center pinion and may be more readily backed up during the setting operation.

It is the object then of the present invention to provide a comparatively frictionless drive for an electric watch which combines the mechanical and electrical impulse in the same operation.

With the foregoing and other objects in view, the invention resides in the novel arrangement and combination of parts and in the details of construction hereinafter described and claimed, it being understood that changes in the precise embodiment of the invention herein described may be made within the scope of what is claimed without departing from the spirit of the invention.

The invention is shown in the accompanying drawings in which:

Figure 1 is a top plan view of the movement as mounted on the pillar plate.

Figure 2 is a cross section showing the balance wheel and part of the train but omitting the ratchet arms.

Figure 3 is a cross section of the setting apparatus.

Figure 4 is a detail view showing the simultaneous occurrence of the electrical and mechanical contact.

Figure 5 is a detail view of the ratchet arms greatly enlarged.

Referring to the drawings, more particularly to Figure 1, a pillar plate 8 supports a battery 9 which is held in place by retaining screws 10 and 11 and which is grounded to the pillar plate

2
8. A terminal 12 is secured to the center post 13 of the battery 9 and is connected at 14 to one side of a coil 15. The lead 16 coming from the coil is connected to a contact spring arm 17 which serves to make both the electrical contact and the mechanical impulse.

A roller table 18 is carried on the balance staff 19 below the balance wheel 20. A pin 21 projecting downward from the underside of the roller table is formed of one half insulation material 22 and the other half conducting material 23. This permits mechanical and electrical engagement simultaneously between the contact arm 17 and the pin 21 when the pin is moving clockwise but gives only mechanical contact on movement of the pin counter-clockwise.

Extending from the coil are pole pieces 24 and 25 terminating respectively in pole faces 26 and 27 which are energized from the coil at intervals 20 depending upon the contact of the arm 17 with the conducting side 23 of the post 21. A balance wheel 20 carried on the balance staff 19 and driven by the electromagnets 26 and 27 has connected thereto the ordinary hairspring 28 and regulator 29. The balance staff 19 is mounted in the usual fashion having oiled pivot jewels and endstones to provide an almost frictionless bearing.

30 A ratchet wheel 30 serves to receive the driving impulse from the ratchet arm 31 and in turn transmits this impulse to a pinion 32, a fourth wheel 33, pinion 34 to a third wheel and pinion (not shown) and from this third wheel pinion to a center wheel 35. All this is ordinary watch construction and does not add anything new to the art.

35 A shaft 36 connected directly to the fourth wheel 33 operates a sweep second hand 37. The center wheel 35 is frictionally held against the shoulder 38 of the center pinion 39 by a spring 40. This friction drives the center pinion 41 to which is connected a minute hand 42. Also connected, and of the usual construction, to the center pinion 41 is a gear 43 having a pinion 44 and an hour wheel 45 which in turn operates an hour hand 46. With the exception of the manner in which the center wheel is frictionally held against the shoulder 38 of the center pinion, this is all usual watch construction.

40 The ratchet arm 31 is formed with narrowed portions 47 and 48 (see Figure 5) and a ratchet engaging tooth 49. The contact arm 17 engages the ratchet arm at 50 to provide the mechanical impulse which is transmitted through the arm 55 31 to the ratchet wheel 30, the movement be-

ing sufficient to advance the ratchet wheel the distance from one tooth to another, the spring retaining pawl 51 engaging the ratchet wheel at 52 to prevent backward movement of the ratchet wheel 30. The weakened portions 47 and 48 allow flexure of the ratchet arm 31 at the proper places with as little expenditure of energy as possible.

A setting stem 53 operates in the usual manner a setting wheel 54 which meshes with gear 55 and through a pair of idler gears turns a gear 43 contacting the center pinion 41 and through a pinion 44 turns the hour wheel 45. It will thus be seen that it is easy to set the hands through slippage between the center wheel and the shoulder of the center pinion. In operation an electric current passing from the battery through the coil 15 energizes the electromagnets 26 and 27 upon contact of the contact arm 17 with the conducting side 23 of the pin 21. This gives a magnetic impulse to balance wheel 20 which through its motion transmits a mechanical movement through the ratchet arm 31 to the ratchet wheel 30 at exactly the same time that the magnetic impulse is given to the balance wheel so that the load is carried by the magnetic force rather than the inertia of a moving balance wheel. The return of the balance wheel brings the insulated side 22 of the pin 21 into contact with the contacting spring arm 11, the ratchet arm 31 returning to its initial position through its inherent spring action until stopped by the pin 56. Flexure at the points 47 and 48 permit the movement of the arm 31 with the minimum expenditure of energy. The motion of the ratchet wheel is intermittent and is transmitted through its pinion 32 and through the train of gears to the indicating hands of the watch.

The period of the balance wheel is regulated so that it has four beats a second, that is one forward and one back to provide a movement of the ratchet wheel equal to a half second movement of the sweep second hand on the seconds dial.

What is claimed is:

An electric watch having hands comprising an electromagnetically driven balance wheel assembly, a train of gears including a ratchet wheel for driving the hands, a contact post formed of a semicylindrical section of electric conducting material and a semicylindrical section of a dielectric material, fixedly carried by said balance wheel assembly, a battery, an electromagnet, a spring contact arm connected to said battery and adapted to engage the contact post on said balance wheel assembly to energize said electromagnet when moving clockwise to impulse said balance wheel, an elongated substantially L-shaped ratchet arm secured at one end and upturned at its free end to form a ratchet wheel engaging prong, said arm being decreased in thickness adjacent its secured end and adjacent the butt of the L to insure transverse flexure of each of the legs of the L, said arm being contacted and moved by contact with said moving spring contact arm to index said ratchet wheel, the flexure of the legs insuring operation of the ratchet wheel, the mechanical impulse transmitted through said spring ratchet arm to said ratchet wheel occurring simultaneously with the electrical impulse imparted from said electromagnet to said balance wheel.
